UNITED STATES PATENT OFFICE

HARRISON B. WALTER, OF CHICAGO, ILLINOIS, ASSIGNOR TO CONTAINER CORPORATION OF AMERICA, OF CHICAGO, ILLINOIS, A CORPORATION OF DELAWARE

SECURING MEANS FOR CLOSURES

Application filed October 26, 1929. Serial No. 402,599.

The present invention relates to fibre or paper board boxes and more particularly to a box of this character provided with means for fastening certain parts thereof together in a secure and practically permanent manner. Among the objects of the invention are to provide a box construction of comparatively simple form, easy to set up and handle, and having parts which may be secured together with a minimum effort to provide a practically permanent connection therebetween.

To these and other ends the invention resides in certain improvements and combinations of parts, all as will be hereinafter more fully described, the novel features being pointed out in the claim at the end of the specification.

In the drawings:

20 Fig. 1 is a perspective view of a box embodying the present invention illustrating a preferred form of construction for securing two parts of the box together;

25 Fig. 2 is a view similar to Fig. 1 showing the cooperating parts in secured relation; and

30 Fig. 3 is a fragmentary detail view of a slightly different form of securing means for one of the parts.

The present embodiment of the invention provides a dependable form of box construction capable of being manufactured at moderate cost and being particularly advantageous for use in the manufacture of paper and fibre board boxes having cooperating cover flaps which are to be secured together. Referring more particularly to the drawings there is indicated at 5 a box which in the present instance is made up with dimensions 35 suitable for employment as a suit or clothing box. Certain features of the construction of the present box form the subject matter of my copending application Serial No. 407,329, filed November 15, 1929, to which reference is made for a full description thereof.

The box 5 is formed from a single blank of sheet material, preferably from fibre or paper board, having appreciable stiffness of texture. The cover flaps indicated respectively at 6 and 7 are hinged to the side walls 50 8, 8 along score lines 9, 9 and preferably somewhat overlap at the central portion of the box.

In the present instance the cooperating cover flaps 6 and 7 are adapted to be secured together by means of a tongue and slit connection. While this tongue and slit connection may be employed to advantage either in boxes of the character described or in other constructions of fibre or paper board having parts arranged to be secured together in like manner, the present description will be limited, for the sake of simplicity, to a box construction.

The tongue, designated as a whole at 10, is 65 preferably but not necessarily, an integral part of the cover member 6. This tongue is adapted to be inserted in a suitably formed slit 11 in the complementary cover member 7. Means are provided on the tongue 10 whereby 70 when the tongue is inserted into the slit 11 it will automatically be engaged therein so as to render it difficult, if not impossible, to remove the tongue without tearing the material of the box. This means, in the present instance, 75 comprises a pair of flap extensions 12, 12 formed integrally with the tongue 10 and at each side thereof. The length of these flap extensions may vary within generous limits, but in the present instance they are shown 80 of a convenient length approximately one-fifth to one-fourth of the length of the tongue proper. In order to provide for accuracy in folding the flap extensions a circular or other shaped opening 13 is formed between the flap extensions and the main part of the cover member 6. In this way the flaps 12, 12 may be bent over against the tongue 10 in a more uniform manner and without the necessity of scoring along the line between the tongue and 90

the flap. The openings 13 tend to facilitate bending of the flap for the reason that they slightly weaken the material along the junction line between the tongue and flap.

5 The flaps 12, 12 are preferably secured to the under face of the tongue 10 in any suitable manner, this being accomplished in the present instance by staples 14, 14. The flaps 12, 12 thus provide projecting shoulders on the 10 under face of the tongue 10 which cooperate with the slit 11 in a manner to be presently set forth. While it is not necessary in every case for the shoulders or abutments on the underface of the tongue 10 to be formed in this 15 manner it is preferable from a manufacturing standpoint. The same result could, however, be obtained by securing independent abutment members on the tongue.

With the box set up as shown it is ready 20 to be closed and sealed by inserting the tongue 10 into the slit 11 as indicated in Fig. 2. With the tongue in this position the edges 15 of the flaps 12 will bear against the edge 16 of the material along the slit 11 and will thus 25 serve as a positive latch for preventing disengagement of the tongue from the slit. In practice it has been found that it is next to impossible to extricate the tongue from the slit without tearing the slit or the tongue or 30 both.

There is preferably provided at each terminal of the slit 11 an opening 17 of appreciable diameter and preferably substantially circular in form although the particular shape 35 of the opening is, in general, immaterial. The preferred method of forming this construction is to provide at the ends of the cutting knife a circular cutter which makes the widened openings. These openings serve the 40 purpose of facilitating the insertion of the tongue in the slit and preventing possible tearing of the material along the extended lines of the slit.

In this connection it may be noted that 45 when a simple slit is formed in a sheet of material the ends of the slit are almost never sharply defined but more usually present a condition which gradually merges from the solid material to the beginning of the cut proper. Accordingly when the material on either side of the slit is moved relatively apart in substantially parallel planes shearing 50 stresses are set up which tend to further extend the slit and this is especially noticeable 55 when the slit is disposed parallel to the grain of the material. Where the slit terminates in a widened opening the shearing stresses are distributed over a greater area of the material and the likelihood of the slit being 60 lengthened by tearing is greatly reduced.

It has been found in practice that the form 65 of slit herein shown has several distinct advantages over a slot. In the first place the process of making a slit is more simple as it requires but a single blade or knife whereas

the slot requires two blades or knives, also, in the case of the slot an additional operation is necessary for the reason that the material in the slot must be stripped or displaced from the slot. Another disadvantage of the slot 70 arrangement is that it does not provide such a secure locking engagement for the tongue.

The form of the invention shown in Fig. 3 is similar to that shown in Figs. 1 and 2 except that in this case the tongue 20 is formed 75 with flap extensions 21, 21 which are not secured to the under face of the tongue proper but are intended to extend outwardly. In securing the cover members together where this form of the invention is used it is necessary to bend under the flaps 21 and hold them thus with the fingers while the tongue is being inserted in the slit.

While a slit has been shown and described 80 for use in connection with the locking tongue of the present invention it is not necessary in every instance that the slit be employed as the novel features of the tongue are capable of cooperating in an effective way with a narrow slot. The slit however is preferred 85 for the reasons above given.

It will thus be seen that the present invention provides an effective means for securing together various parts of fibre or paper board constructions and is particularly 90 advantageous for securing together the closure members of a box. It is further apparent that the securing means may be readily engaged to form a practically permanent seal 95 for the box, it being unnecessary to employ 100 cord, gummed tape or any other type of securing means in conjunction therewith. The construction of the present invention is particularly advantageous for use in suit boxes and in boxes of a similar nature as it is possible 105 to set up the box, pack a suit or other article therein and secure it for further handling with a great saving of time over the old method which included tying a cord 110 around the box.

While the present description sets forth a preferred embodiment of the invention, numerous changes may be made in the construction without departing from the spirit of the invention, and it is therefore desired that 115 the present embodiment be considered in all respects as illustrative and not restrictive, reference being had to the appended claim rather than to the foregoing description to indicate the scope of the invention.

I claim:

A box of fibre or paper board comprising 120 two cooperating cover flaps, one of said flaps having a slit therein, a tongue projecting from the outer free edge of the other of 125 said flaps and adapted to engage within said slit, flap extensions projecting laterally on each side of said tongue bent over in the direction of the center line of said tongue and secured to the under side thereof, said flap 130

extensions presenting shoulders along a line substantially at right angles to the fold of said flap extensions, said shoulders being somewhat spaced from the surface of said tongue whereby an abutment will be provided which is adapted to contact the edge of the material at one side of said slit to prevent free withdrawal of the tongue therefrom.

Signed at Chicago, Illinois, this 24th day
10 of October, 1929.

HARRISON B. WALTER.
